DESIGN FOR A HAT

Irwin B. Simon, San Francisco, Calif.

Application February 25, 1936, Serial No. 61,346

Term of patent 3½ years

To all whom it may concern:

Be it known that I, Irwin B. Simon, a citizen of the United States and a resident of the city and county of San Francisco, State of California, have invented a new, original, and ornamental Design for a Hat, of which the following is a specification, reference being had to the accompanying drawing, forming part thereof, and in which

Figure 1 is a perspective view of the hat constituting my new design; and

Figure 2 is an enlarged detail showing of the material disclosed in Figure 1.

The entire hat is made of the combination of elements set forth in Figure 2 and fragmentarily illustrated in Figure 1, the characteristic feature residing in the braid.

I claim:

The ornamental design for a hat as shown and described.

IRWIN B. SIMON.
